CLAIM

The ornamental design for a self-service terminal, as shown and described.

DESCRIPTION

FIG. 1 is a left-front perspective view of a self-service terminal showing our new design;

FIG. 2 is a right-front perspective view of the self-service terminal design of FIG. 1;

FIG. 3 is a front view of the self-service terminal of FIG. 1;

FIG. 4 is a rear view of the self-service terminal of FIG. 1;

FIG. 5 is a left-side view of the self-service terminal of FIG.

1;

FIG. 6 is a right-side view of the self-service terminal of FIG. 1; and,

FIG. 7 is a top view of the self-service terminal of FIG. 1. The bottom of the automated transaction machine is flat and devoid of ornamentation.

The broken lines shown in the drawings represent portions of the Automated Transaction Machine that form no part of the claimed design.
